UNITED STATES PATENT OFFICE.

FREDERIC C. WEIR, OF CINCINNATI, OHIO.

RAILWAY-FROG.

SPECIFICATION forming part of Letters Patent No. 319,362, dated June 2, 1885.

Application filed August 14, 1884. (No model.)

To all whom it may concern:

Be it known that I, FREDERIC C. WEIR, a resident of Cincinnati, in the county of Hamilton and State of Ohio, have invented certain new and useful Improvements in Railway-Frogs, of which the following is a specification.

My invention relates to an improvement in railway-frogs, and particularly to that class known as "channel-iron frogs."

One of the objects of my invention is to provide filling-blocks which will furnish vertical support to the rails as well as lateral support to the channel-irons.

Another object of my invention is the employment of a through-bolt for binding the parts of the frog together. Through-bolts have not been hitherto employed in channel-iron frogs; but three series of bolts are used, binding each wing of the channel to its abutting rail separately.

My method of strengthening and uniting the parts is at once cheaper and more durable than three series of bolts hitherto employed, all of which will be fully explained in the description of the accompanying drawings, in which—

Figure 1 is a top plan view of my invention; Fig. 2, a cross-section on line $\alpha\alpha$, Fig. 30 1; Fig. 3, a side elevation of one rail, showing the block and channel-plates in section. Fig. 4 is a perspective view of one of my improved filling-blocks.

A A' represent the ordinary wing-rails of a 35 railway-frog; B B', the point-rails, which may be united or fitted together by swaging or grooving, as desired.

D D represent the ordinary channel-irons, the wings of which fit the webs of the rails 40 forming the frog.

C C represent filling-blocks, the contour of which fits the channels D. c represents a hole or recess pierced in the block C, for the admission of the through-bolt E. I have shown two forms of this filling-block—one in Fig. 2, in which the block is pierced with a hole larger than the bolt itself, and one in Fig. 4, which shows a recess or opening adapted to receive the bolt. The base of block C

50 rests upon the channels D, and the ledges a project upward and abut against the under side of the rails, thereby furnishing also a ver-

tical support for the rails as well as strengthening the channel-irons and the frog structure.

55

When filling-blocks C are employed, a through-bolt E with a nut-lock, can be employed to unite the parts of the frog together.

The omission of the shoulders a could be made, and still embody a feature of my invention specified in the first claim.

C' represents a filling-block placed forward of the main point-rail, and having lugs i i projecting rearward and grasping the channel upon each side of the web of the point-rail, so as to hold the channel up to the point. The bolt draws these parts together and holds them in a substantial position.

Instead of a continuous channel-iron, two or more U-shaped irons, one placed in front 7c of the other, might be employed with good results.

When the filling-blocks and through-bolts are used in connection with the channel-irons D, the latter may be shortened, instead of having them extend as far to the rear as I have here shown, and the filling-blocks employed in rear as well as in front of the channel-irons.

Another modification would be to have my filling-pieces rest upon and be held in position by a through-bolt, which would clamp the end of the filling-pieces against the wings of the channel and preserve the space between the rails, and yet unite the parts together to form a substantial structure.

85

I claim—

1. A railway-frog composed, substantially, of wing and point rails, channel-irons D and filling-pieces, and through-bolt E, adapted to clamp the structure and preserve the space between the rails, substantially as described.

90

2. In combination with a channel-iron railway-frog, a filling-block, C, fitted to the channels D, substantially as specified.

3. A filling-block, C, provided with lugs i, 95 in combination with the channel-irons for supporting the main point-rail, substantially as specified.

In testimony whereof I have hereunto set my hand.

FRED. C. WEIR.
